DESIGN FOR A MERCHANTISE DISPLAY DEVICE OR SIMILAR ARTICLE

Edwin P. Price, Jr., Wilmette, Ill.

Application April 26, 1946, Serial No. 128,982

Term of patent 7 years

(Cl. D80—9)

To all whom it may concern:

Be it known that I, Edwin P. Price, Jr., a citizen of the United States and residing in the village of Wilmette, in the county of Cook and State of Illinois, have invented a new, original, and ornamental Design for a Merchandise Display Device or Similar Article, of which the following is the specification, reference being had to the accompanying drawings, forming a part thereof.

On the drawings:

Fig. 1 is a front elevation of my merchandise display device showing my new design.

Fig. 2 is a top plan view thereof.

Fig. 3 is an elevation taken of the right hand end portion of Fig. 1.

I claim:

The ornamental design for a merchandise display device or similar article, substantially as shown.

EDWIN P. PRICE, JR.
